O Francis Jenkins

Inventor

UNITED STATES PATENT OFFICE

CHARLES FRANCIS JENKINS, OF WASHINGTON, DISTRICT OF COLUMBIA, ASSIGNOR TO JENKINS LABORATORIES, OF WASHINGTON, DISTRICT OF COLUMBIA, A CORPORATION OF THE DISTRICT OF COLUMBIA

SPLIT SWITCHING GEAR

Application filed September 6, 1928. Serial No. 304,354.

This invention relates to radiovision receivers, particularly to switching gear therefor, which permits a simplicity of apparatus not otherwise possible.

5 It is designed as an essential in the practice of the art in the manner shown in co-pending case No. 242,989.

The main object is to simplify the switching mechanism, and at the same time deliver 10 maximum current to all lamps in succession without any current by-pass through other lamps.

With these and other objects in view the invention consists in the novel combination 15 of elements herein described and illustrated and particularly pointed out in the claims.

In the drawings, Figure 1 is a front view of a multiple lamp frame; Figure 2, an edge view thereof; Figure 3 a detail of one of the 20 lamps, shown here as a luminescent lamp, though suitable filament lamps may be used; and Figures 4 and 5 a schematic drawing of the switching gear employed to light the lamps singly and in a given sequence.

25 In the figures, A is a lamp frame; B and B are lamps; E is a ground glass screen which may or may not be used in front of the lamps; F is the cathode glow-target of the lamps (Fig. 3). G is a resistance in the lamp leads, 30 and H a condenser. K is a stationary multiple brush commutator having a moving segment or contacting member L, fastened to arm M, sweeping over the flexible brush ends N. Q is a 6-segment commutator, with 35 its brush R, mounted on arm S.

For purposes of easier illustration, assume the frame A to contain 2304 lamps, divided 40 into six banks of 384 lamps each. There are six circular rows of stationary brushes N (Fig. 5), and correspondingly six electrically independent moveable contacts L on six electrically connected arms M (Fig. 4). Each 45 of these contact arms is electrically connected to its respective collector ring, as at Y and Y^o, Fig. 5.

The commutator Q has six stationary segments, one segment for one of each of the 50 six rows of brush contact arms of commutator K, and therethrough to the six banks of lamps. That is, for the 2304 lamps, each

row of contact segments of the commutator K needs have only 384 brushes, and the commutator K may be small, for it rotates six times to light the entire 2304 lamps. As it sweeps over the 384 brushes, only a single 55 lamp is lighted, because the 384 lamps of a single bank are in circuit only through the second commutator Q.

When commutator K makes its second revolution it lights the lamps one at a time in 60 the second bank of lamps, because commutator Q has moved its brush onto the second segment, which feeds current into the second row of segments of commutator K. Continued rotation of both commutators will 65 eventually light all of the lamps.

As the functioning of the other elements shown in the drawing is described in co-pending case No. 242,989, and the same is not essential in a complete understanding of this 70 invention, perhaps no description here is needed.

The particular advantage of this invention is that a commutator of but a few inches in 75 diameter is just as satisfactory as a commutator six times as large of consequent heavy and clumsy structure.

What I claim, is—

1. In combination a bank of current translating devices arranged in coordinate rows, 80 and means for connecting each device successively in circuit comprising a group commutator having a group contact for each row of said devices, another commutator having a contact for each of said devices, the contacts in said other commutator being arranged in tiers, a movable brush for each of said tiers, and means for connecting said brushes to the contacts of the first commutator. 85

2. In combination a lamp bank comprising a plurality of television reproducing lamps arranged in coordinate rows, a first commutator having a group contact for each row 90 of lamps, another commutator having a contact for each lamp, said contacts being arranged in tiers, a brush assembly for said tiers of contacts, and a slim ring device carried by said brush assembly for connecting 100

said tiers to the contacts of the first commutator.

3. In a television system means for connecting the lamps of a reproducing lamp bank successively in circuit, comprising a group commutator having fixed contacts, each corresponding to a row of lamps, and another commutator having the contacts arranged in tiers, and means for connecting the fixed contacts of the first commutator to the brushes of the second commutator.

In testimony whereof I have affixed my signature.

CHARLES FRANCIS JENKINS.
